CARD CARRIER

Filed Sept. 5, 1925

UNITED STATES PATENT OFFICE

GEORGE H. DAWSON, OF CAMBRIDGE, MASSACHUSETTS, ASSIGNOR, BY MESNE ASSIGNMENTS, TO REMINGTON RAND INC., OF NEW YORK, N. Y., A CORPORATION OF DELAWARE

CARD CARRIER

Application filed September 5, 1925. Serial No. 54,841.

This invention relates to a card carrier which is primarily adapted for use in a visible overlapping index whereby the lower margins of the cards exhibit exposed edges.

- 5 It is an object of this invention to provide an address slip upon which a plurality of addresses may be written and which may be associated with the card so that the name and address will be in substantial alinement. 10 The address slip is preferably made removable with respect to its support for typing the address thereon, or for other purposes.

The invention comprises the novel structure and combinations hereinafter described 15 and more particularly pointed out and defined in the appended claims.

In the accompanying drawings, which illustrate a preferred embodiment of this invention and in which similar reference 20 numerals refer to similar features in the different views:

Figure 1 is an elevational view of the assembled card holder, card and address slip;

Figure 2 is an elevational view of the card holder and attached address slip with the card removed;

Figure 3 is an enlarged sectional view upon the line III—III of Figure 1, and

Figure 4 is a plan view of the unfolded 30 address slip.

As illustrative of this invention, there is shown a card holder comprising a rectangular spacing bar 1 which is adapted to fit in the guideways or channels of a tray or frame, 35 as is well known in the art. A hinge member 2 is stapled or secured to the spacing bar 1. This hinge preferably consists of kraft paper having a weakened hinge line indicated at 3, although any other suitable material may 40 be used. The upper portion of the hinge member carries a pair of eyeleted disks 4 which are located adjacent the lateral margins of the hinge member. The record card C is adapted to be supported upon these eyeleted studs and for this purpose it is provided with suitable lateral notches 5.

It will be noted that the hinge member extends a considerable distance below the disk 4 and upon one-half of the lower portion 45 thereof are secured a pair of eyeleted disks

6 which are adapted to sustain the address slip 7. This address slip in the present instance is shown as consisting of a folded sheet having suitable notches 5 in its lateral edges for engagement with the eyeleted disks 6. 55 It will be noted that the lateral notches in the address slip are located approximately in the medial line of the folded slip and the same is so supported that it suspends a suitable distance below the hinge member 2 in 60 order that the lower edge of the address slip may be situated substantially in alinement with the lower edge of the card C.

In Figure 4 the address slip is shown in plan view and it will be noted that it has 65 four addresses written upon one face—two addresses being adjacent the end margins and the other two addresses being adjacent the crease where the slip folds. The opposite side of the slip is adapted to contain the 70 same number of addresses. The addresses should be so arranged that they will always be in proper position whether the slip is inverted or turned back-side foremost. By unfolding the slip and folding it in a reverse 75 manner, four additional spaces will be provided for containing addresses, according to the position in which the address slip is attached. Other notations instead of or in addition to the addresses may be put on the 80 slip 7. However, instead of a folded sheet, the address slip may consist of a single card providing spaces for two addresses on one side and two addresses on the other side. The lower margin of the address slip is exposed through a recessed margin on the card 85 C which is sufficiently cut away to exhibit the address on the slip, as indicated at 8.

Accordingly, the address slip will show one address at a time. This address should, of course, be the present address of the client or customer whose name appears upon the index card C. When such customer changes his address, the changed address may be written upon the upper margin of the front face of 95 the slip and the slip will be inverted to present the new address through the recessed portion. If the customer or client changes his address again, the rear face of the slip may be utilized just as the front. If further 100

changes are necessary, the slip may be folded in a reverse direction for utilizing the other faces of the sheet. In this manner, the index slip will always show both the present and past addresses of the client or customer.

From the foregoing, it will be appreciated that a novel form of card carrier has been provided in which the address of the client is contained upon the removable slip which 10 presents the address in alinement with the name on the lower margin of the index card. This address slip always provides means for showing the correct address and at the same time reserving, if desirable, the former addresses of a client.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In a card carrier, a supporting bar, a 25 hinge member secured to the supporting bar, a card removably supported upon said hinge member and having a portion of its margin recessed, and an address slip supported upon said hinge member with its lower margin exposed through the recessed portion of said card.

2. The combination with a card carrier, of a card removably supported thereon and having a portion of its lower margin recessed, 35 and an address slip associated with said card and carrier and having its lower margin exposed through said recessed portion.

3. The combination with a card carrier, of a card removably supported thereon, said 40 card having a lower recessed portion, and a folded address slip removably attached to said carrier and having its lower margin exposed through said recessed portion.

4. In a card carrier, a hinge member having a pair of spaced studs, a card removably mounted upon said studs and having a portion of its lower margin recessed, and a second 45 pair of studs mounted upon said hinge member and an address slip removably supported upon said second pair of studs and having its margin exposed through said recessed portion.

5. The combination with a card carrier, of a card removably supported thereon, and 55 means on said carrier for removably supporting an address slip, said address slip being supported substantially upon a medial line whereby the same may be inverted or turned back-side foremost for the purpose set forth.

6. The combination with a card carrier, of a card removably supported thereon and having a lower recessed margin, and an address slip so supported as to expose its lower margin through the recessed margin of said card.

7. The combination with a holder card hav-

ing means for detachable engagement in a frame, of a record card removably mounted upon said holder card, and an address slip removably supported on said holder card adjacent said record card and having a marginal portion projecting beyond the adjacent marginal portion of said record card for exhibiting an address thereon.

In testimony whereof I have hereunto subscribed my name:

GEORGE H. DAWSON.
